UNITED STATES PATENT OFFICE

CARLOS E. BRONSON, OF KEWANEE, ILLINOIS, ASSIGNOR TO KEWANEE BOILER CORPORATION, OF KEWANEE, ILLINOIS, A CORPORATION OF DELAWARE

BOILER

Application filed October 25, 1929. Serial No. 402,386.

The present invention concerns heaters, boilers and like or similar appliances, particularly those made of sheet-metal and aims to provide a structure of this general character having certain structural and manufacturing advantages.

One object of the invention is to supply a boiler or heater which is compact in construction, economical in use, and which may be made at relatively low cost.

To this end, the design of the apparatus is such that, in a welded boiler, the required amount of welding is reduced to a minimum and the cost of production correspondingly lessened.

Accordingly, the structural elements entering into the appliance as to their shapes, forms, locations, relation to other members, etc., are such that the boiler or heater may be produced or manufactured with the least amount of material, labor and expenditure of funds.

The manner in which such aims or purposes and others are attained may be understood by those skilled in this art from a consideration of a preferred embodiment of the invention illustrated in the accompanying drawings, forming a part of this specification, and throughout the views of which like reference numerals have been employed to designate the same parts.

In these drawings:

Figure 1 is a central, longitudinal, vertical section through the boiler;

Figure 2 is a front elevation of the boiler;

Figure 3 is a vertical cross-section through the boiler on line 3—3 of Figure 1;

Figure 4 is a fragmentary, vertical cross-section on line 4—4 of Figure 1; and

Figure 5 is a side elevation of the wrapper sheet which in part encloses the auxiliary combustion-chamber.

Referring to the several figures of the drawings, it will be observed that the novel and improved sheet-metal boiler or heater structure comprises a front, upright, metal plate 11 having a substantially semi-circular, top edge and parallel, vertical edges, its lower, horizontal margin being provided with an inturned flange 12 for the greater portion

of its length corresponding to the width of the fire-box, the boiler including also a rear-wall plate 13 of like contour with a similar, internal flange 14 along its bottom edge.

The main shell sheet 15 is bent to harmonize with the shapes of the front and rear walls between which it fits and to the rear and front faces of which respectively it is suitably welded, the bottom, side edges of such plate having inwardly-projecting flanges 16, 60 16 the ends of which are likewise welded to the flat faces of the front and back wall plates.

The fire-box or fuel-combustion chamber 20 has a front wall plate 17 with an arched, top edge and upright, parallel edges, the plate 65 being of less width than the corresponding dimension of the boiler to provide for side water-legs in the latter with proper circulation therein.

A door opening 18 is provided in the outer plate 11 and a corresponding, registering aperture 19 is present in the inner plate 17, the space between the two plates affording a front water-leg 23 sealed around the doorway by a ring composed of a bent plate 22 and its companion straight plate 21, both located between the outer and inner plates 11 and 17 and welded thereto and to one another.

Of course, such doorway is supplied with the customary fire-door, but this has not been shown.

A water-leg 24 is present at the back of the fire-box 20 and is formed between the outer, wall plate 13 and an inner, rectangular plate 25 spaced therefrom and having along its top border an outturned flange 26 welded to the inner surface of member 13, the flange 14 of the latter being welded to plate 25 along its bottom margin.

The crown-sheet or inner wall of the fire-box or main combustion-chamber reaches from the inner face of element 17 to the inner surface of member 25 having its edges welded to each of these, such crown-sheet being bent to form a curved or arched crown-sheet proper 27 and parallel, vertical side-walls 28, 28, the flanges 16, 16 of plate 15 being welded to the outer faces of the parts 28, 28.

Such plate 27, 28, 28 at its rear end is cut away along the lines 29, 31 to provide a top aperture of substantial size to afford communication with an upper, supplemental combustion-chamber 30 formed by a flue-sheet 32 whose lower, curved edge conforms to, overlies, and is welded to the outer surface of the crown-sheet 27, 28, 28 and by a sheet having a wide, horizontal top 33, parallel, wide, side-walls 34, 34, and narrower, downwardly-extending, side-wall sections 35, 35.

The parts 33, 34, 34 extend from plate 32 to plate 13 and have their edges welded to each and the extensions 35 have their front edges likewise welded to the flue-sheet, and, where their lower ends continue down beyond the ends of the flue-sheet, they overlap and lie flat against the outer surface of the crown-sheet member 27, 28, 28 and are welded to it, not only adjacent to the margins 29, 29 but also the full length of the borders 31, 31.

Sections 35, 35 are of a width to overlap the upright edges of plate 25 to which they are welded and sections 34, 34 continue down far enough to overlap the ends of flange 26 to which they are welded.

Wall 13 just above the rear water-leg 24 and beneath the plate 33 has a doorway 36 therethrough fitted with a suitable door 37 giving convenient access to the interior of the auxiliary combustion-chamber 30, to the flue-sheet and to its flues 38, 38 which connect also with the front wall or header 11, longer flues 39, 39 mounted in the front and rear walls joining the front connection 41 with the stack connection 42 as in the usual way.

The various parts are strengthened in the customary manner by stays which are shown and the boiler is equipped with other ordinary fittings also illustrated, but none of which require further mention.

The manner in which the members are shaped and combined to allow ease and economy in welding should be observed and attention is also directed to the fact that the opening or doorway 36 extends through only one thickness of metal rather than through a hollow, water-filled wall, thus rendering possible a substantial saving in the amount of welding required at this point.

Obviously, the invention, as defined by the appended claims, is not limited to this particular embodiment which is presented by way of convenient example only, and many changes may be incorporated therein without departure from the substance of the invention and without the sacrifice of any of its salient advantages.

I claim:

1. In a metal boiler, the combination of outer, front and rear plates, an outer shell secured to said plates, an inner rear plate spaced from said outer rear plate forming a water-space between them, a bottom flange on one

of said rear plates welded to the other rear plate, a top flange on said inner rear plate welded to said outer rear plate and forming the top wall of said water-space, a bent plate, forming a crown-sheet and depending inner side walls for the fire-box of the boiler, cut away at the back portion of its top and welded to said inner rear plate, a flue-sheet welded to said bent plate adjacent to the aperture formed by said cut-away section, and a bent sheet between and welded to said flue-sheet and said outer rear plate and also welded to the ends of said top flange of said inner rear plate and having narrower side downward extensions welded to said flue-sheet, a crown-sheet plate around the lower portion of its cut-away section and to the edges of said inner rear plate, said outer rear plate having an opening therethrough between said bent plate and water-space affording access to said flue-sheet, and a closure for said opening.

2. In a metal boiler, the combination of outer, front and rear plates, an outer metal shell secured to said plates, an inner rear plate spaced from said outer rear plate forming a water-space between them and having a flange around its top edge welded to said outer rear plate, the latter having a doorway therethrough above said water-space and flange, a door for said doorway, a bent plate forming a crown-sheet and inner side-walls for the boiler fire-box welded to said inner rear plate and cut away at its back top portion, a flue-plate welded to said crown-sheet plate, and a bent plate between and welded to said flue-plate and outer rear plate around said doorway and having narrower downward extensions welded to said flue-sheet, a crown-sheet plate and to the opposite edges of said inner rear plate.

In witness whereof I have hereunto set my hand.

CARLOS E. BRONSON.
